UNITED STATES PATENT OFFICE.

EDWARD E. SMALL, OF PORTLAND, OREGON.

GAS GENERATOR AND BURNER.

1,329,862.

Specification of Letters Patent.

Patented Feb. 3, 1920.

Application filed June 17, 1919. Serial No. 304,756.

To all whom it may concern:

Be it known that I, EDWARD E. SMALL, a citizen of the United States, and a resident of Portland, in the county of Multnomah and State of Oregon, have made certain new and useful Improvements in Gas Generators and Burners, of which the following is a specification.

This invention relates to an improvement 10 in gas generators and burners, and one of the principal objects thereof is to provide an improved gas generator and burner especially adapted for use in ranges, heating stoves, furnaces and the like.

15 Another object of the invention is to provide an improved generator and burner adapted to use coal oil as a fuel, the construction being such that the oil is volatilized in a chamber forming part of the 20 burner and is fed in the form of gas from a hollow finger communicating with the chamber, the means for vaporizing and feeding the gas being contained in the burner.

Another object of the invention is to provide 25 an improved gas generator and burner which will be extremely simple, durable, efficient in operation and inexpensive to manufacture. With these and other objects in view which will become apparent as the description 30 proceeds, the invention resides in the construction, combinations and arrangement of parts hereinafter more fully described and claimed and illustrated in the accompanying drawing in which like characters of reference indicate like parts throughout the several figures of which,

Figure 1 represents a vertical sectional view taken through the burner and generator constructed in accordance with my invention.

Fig. 2 represents a side elevational view thereof.

Fig. 3 represents a horizontal sectional view taken on the plane indicated by the 45 line 3—3 of Fig. 1.

Fig. 4 represents a plan view of the plate used for spreading the flame.

Fig. 5 represents a transverse sectional view taken through the plate.

50 Referring more particularly to the drawing, 1 indicates an annular pan into which a small amount of oil is fed in order to start the burner. This oil is drawn from a reservoir or tank, not shown, through a pipe, not 55 shown, and enters through an opening 10 provided in the bottom of the pan. The

pan is arranged below the burner which consists of a lower annular gas chamber 9, and an upper annular gas chamber 8 connected on the side of the burner through a passage 60 11 arranged at one side of the body of the burner, such passage being of relatively large cross sectional area in order to allow for circulation of gas from the lower to the upper chambers.

65 The burner has a central air passage 12 extending therethrough, this passage being enlarged as at 13 in the body of the burner between the upper and lower gas chambers, and arranged in the enlarged portion 70 13 and resting on the lower wall thereof is a flame spreader or plate 4 provided with a central rib 14. This plate is used for the purpose of spreading the flame in the body of the burner.

75 Connecting with the upper gas chamber 8, at a point diametrically opposed to the passage 11, is a hollow finger 15 which curves upwardly and over toward the center of the burner, said finger being provided 80 with a restricted port 7 arranged approximately in alinement with the passage 12 through the burner.

Oil for the burner may be fed through a pipe to the inlet tube 2 communicating with 85 the lower gas chamber 9 and which projects down through the pan 1. From the foregoing description taken in connection with the drawing, the operation of the burner will be readily understood. Oil may be fed to 90 the lower gas chamber through the tube 2. Upon starting the burner a small quantity of oil is drawn into the pan 1 and ignited. The flames from this oil will impinge against the body of the burner, thus raising 95 its temperature sufficiently to volatilize the oil as it is fed into the lower gas chamber. The gas thus generated finds its way up through the passage 11, into the upper chamber 8 and from there through the finger 15 100 to the port 7, from which it is directed downwardly through the upper end of the air passage 6 against the flame spreader or plate 4. The flames from the pan 1, before the pan has burned out will ignite the gas as 105 the latter is ejected from the port 7. The flame directed into the body of the burner will serve to maintain the temperature of the gas chambers sufficiently high to continue the volatilization of the oil as it is fed 110 to the burner.

Although I have described the preferred

embodiment of my invention, I may desire to make such changes in the construction, combination and arrangement of parts thereof, as do not depart from the spirit of 5 the invention and of the scope of the appended claim.

I claim:

A gas generator and burner comprising a body formed to provide spaced upper and 10 lower annular chambers and having formed in one side a passage communicating with said chambers, said body being provided centrally with a relatively large chamber in non-communicating relation to said first 15 named chambers and being further provided

with openings communicating with said central chamber and leading through the top and bottom of the body, a pipe member rising from said body at its side opposite said passage and communicating with the upper of said first named chambers, said pipe being curved to extend over the center of 20 said openings and being provided with a perforation in alinement with the longitudinal axis of said openings, a plate disposed within said central chamber, and a priming pan beneath said body, the lowermost of said first named chambers being adapted for connection with a fuel supply. 25

EDWARD E. SMALL.
